UNITED STATES PATENT OFFICE

154,271

DESIGN FOR A GUARD FOR CHILD'S CHAIR

Jacob G. Heim, San Gabriel, Calif.

Application June 9, 1947, Serial No. 139,551

Term of patent 14 years

(Cl. D15—1)

To all whom it may concern:

Be it known that I, Jacob G. Heim, a citizen of the United States, residing at San Gabriel, in the County of Los Angeles and State of California, have invented a new, original, and ornamental Design for a Guard for Child's Chair, of which the following is a specification, reference being had to the accompanying drawing, forming part thereof.

Fig. 1 is a front elevational view of a guard for child's chair showing my new design;

Fig. 2 is a rear elevational view;

Fig. 3 is a side elevational view; and

Fig. 4 is a bottom view showing my new design.

I claim:

The ornamental design for a guard for child's chair, as shown.

JACOB G. HEIM.
